UNITED STATES PATENT OFFICE

97,354

DESIGN FOR A COMBINED MUFF AND HAND BAG

Rudolph Lobel, New York, N. Y.

Application August 30, 1935, Serial No. 58,370

Term of patent 3½ years

To all whom it may concern:

Be it known that I, Rudolph Lobel, a citizen of the United States and resident of New York city (Borough of Manhattan), in the county and State of New York, have invented a new, original, and ornamental Design for a Combined Muff and Handbag, of which Fig. 1 is a view in side elevation; and Fig. 2 a view in end elevation of a combined muff and handbag showing my new design.

The dominant feature of the design consists of the series of tubes which extend continuously along the sides and bottom of the combined muff and handbag to produce a roll effect.

I claim:

The ornamental design for a combined muff and handbag substantially as shown and described.

RUDOLPH LOBEL.
